SELECTIVE MAGAZINE PENCIL

Wilhelm Dürler, Pforzheim, Germany, assignor
to Lütz & Weiss G. m. b. H., Silber & Metall-
warenfabrik, Pforzheim, Germany, a limited-
liability company

Application February 10, 1939, Serial No. 255,664
In Germany February 23, 1938

4 Claims. (Cl. 120—14)

This invention relates to a selective magazine pencil with two mutually shiftable and rotatable cases fixable in telescoped position, of which cases the rear one carries a feed rod and the front one the lead holders which are longitudinally shiftable by means of the feed rod against the action of return springs.

In the known selective magazine pencils of this type the feed rod fitted behind the rear ends of the lead holder shanks must also be pushed back for retracting the lead holders with the result that the cases come into the extended position in which the pencil is of inconvenient length for carrying in the pocket. Furthermore, the pushing back of the feed rod necessary for carrying the pencil in the pocket renders inconvenient the manipulation in the known pencils.

This disadvantage is overcome by the pencil according to the invention, the novelty consists in that space for accommodating the feed rod is provided between the knobs on the rear end pieces of the lead holder shanks which knobs project through the longitudinal slots in the guide sleeve accommodating the shanks and their return springs, in such a manner that the feed rod does not require to be pushed back for returning the lead holders into their inoperative position, but can be pushed to the side in the space between the outer case and the guide sleeve so that it passes out of the range of the knob actually pushed forward.

By the invention the two cases remain in the telescoped position even when the lead holders are retracted, with the result that the pencil in its packed state is of a length which allows it to be comfortably placed in the waistcoat pocket. To attain this packed state, it is only necessary to exert a brief turning pressure on the two cases in opposite directions, by which pressure the front end of the feed rod slides off the guide knob of the lead holder shank and thus liberates the shank for jumping back under spring action.

An embodiment of the invention is illustrated by way of example in the accompanying drawing, in which:

Fig. 1 shows in longitudinal central section a selective magazine pencil with extended cases,

Fig. 2 shows the pencil partly in elevation and partly in longitudinal section, the cases being in telescoped position and locked in this position,

Fig. 3 is a similar view to Fig. 2 but with the locking device disengaged,

Figs. 4 and 5 are cross sections on line 4—5 of Fig. 1 with the feed rod retracted or pushed for-

ward into the annular space between the lead holder guide sleeve and the pencil case,

Fig. 6 is a cross-section on line 6—6 of Fig. 2 with locking device engaged,

Fig. 7 is a cross-section on line 7—7 of Fig. 2 with locking device disengaged.

The selective magazine pencil has as outer casing two mutually shiftable and rotatable cases *a* and *b*.

In the front case *a* a guide sleeve *c* having longitudinal slots *c* is secured at its front end in such a manner that between the case *a* and sleeve *c* a free annular space *d* is formed (Figs. 4 and 5) into which the knobs *e* on the rear end pieces *e* of the shanks *e* of the lead holders *e* project. The guide sleeve *c* is closed at its front end by a plate *c* with apertures for the shanks *e* and forming an abutment for the front ends of return springs *f* whose rear ends bear against the rear end pieces *e* under slight preliminary compression. A plate *g* is fixed on the rear end of the guide sleeve *c* and carries a locking knob *h*.

A cup *i* is fitted in the rear case *b* which cup carries a feed rod *k* extending into the annular space *d* and the cup *i* has in its bottom an aperture in which a tube *m* is fixed. The front portion of this tube projecting from the bottom of cup *i* forms a pair of nippers *n* with claws *n* and inwardly directed protrusions *n*. The tube *m* also accommodates a rod *o* on the front end of which a disengaging knob *o* is mounted which extends into the pair of nippers *n* whereas its rear end is screw-threaded for receiving an end cap *p*. A ring *m* is inserted in the tube *m* serving as guide for the disengaging knob rod *o* and as abutment for a pressure spring *q* which bears at its rear end against a collar *o* fixed on rod *o*. This rod can be shifted in longitudinal direction in the tube *m* by pressure exerted on the cap *p* (Fig. 3) but not rotated. For this purpose the rod *o* has a longitudinal groove *o*, into which projects a pin *r* or the like in the ring *m* (Fig. 1). If the disengaging knob *o* is forced between the protrusions *n* (Fig. 3) the claws *n* are spread. The space between the tube *m* and the case *b* or the cup *i* inserted in this case serves as magazine for spare leads, the screw cap *p* forming a lid for this magazine.

Colored marks *a* are provided on the periphery of the case *a*, and a mark *b* on the case *b* can be selectively brought into register with the marks *a* by turning the cases *a* and *b* the one relatively to the other. Thus, the feed rod *k* in the annular space *d* comes behind the selected knob *e* which, if the cases *a* and *b* are pushed together,

is shifted from the position shown in Fig. 1 into that shown in Fig. 2 against the action of its associated return spring *f*. At the same time the lead holder *e* connected to the shifted knob *e*₁ 5 is moved forward until it projects from an aperture *a*₂ in the pointed front end of case *a*. To prevent the lead holder *e*, which has just been brought into position for writing, from jumping back, the claws *n*₂ when they come within the 10 range of the knob *h* engage over this knob and securely hold the two cases *a* and *b* in their telescoped position. In this position the selective magazine pencil is so short, that it can be conveniently placed in the waistcoat pocket even with 15 a lead in position for use. If, however, the lead holder *e* is to be retracted before placing the pencil in the pocket, it is not necessary to push apart the cases *a* and *b* but a slight relative turning movement between the two cases is sufficient 20 to bring the feed rod *k* out of the range of the knob *e*₁ (Fig. 5), with the result that this knob becomes free and is moved back into its inoperative position under the action of its compressed return spring *f*. Only for advancing another 25 lead into the writing position is it necessary to first shift apart the cases *a* and *b*. This is effected in the example illustrated with the aid of the pressure spring *s* which bears under slight compression at its front end against the rear end of 30 the case *a* and at its rear end against the cup *i*. When the cases *a* and *b* are telescoped, the pressure spring *s* is compressed (Fig. 3). It becomes operative when the nippers *n* are disengaged from the knob *h*, this being effected by pressure 35 exerted on the cap *p* in the direction of the arrow *A*.

I claim:

1. A selective magazine pencil, comprising in combination a rear case, a front case axially displaceable and rotatable relatively to said rear case, a sleeve fixed in and forming with said front case an annular space and having a plurality of longitudinal slots, a plurality of lead holders corresponding to the number of slots in said 40 sleeve and accommodated in said front case in front of said sleeve, shanks one extending rearwardly from the rear end of each of said holders into said sleeve, end pieces one on the rear end of each of said shanks, knobs projecting laterally 45 outwards from each of said end pieces through one of said slots into said annular space, and a feed rod fixed in said rear case and extending into said annular space, said rod adapted to be selectively brought into axial alignment with one 50 of said knobs by relatively turning said cases and on the axial relative displacement of said cases to shift the selected lead holder into operative position through the intermediary of its end piece and shank, means for securely locking said 55 cases in axially displaced position, and return springs one on each of said shanks and each adapted to be compressed on the advancement of its associated lead holder and to return same into its initial position with the associated shank end 60 piece and knob when said feed rod is moved off the selected knob into the position between the knobs by the relative turning of said casing.

2. A selective magazine pencil as specified in

claim 1, in which the means for locking the cases in their axially displaced position comprise in combination a locking knob on the rear end of the sleeve, a pair of nippers at the rear end of the rear case, claws on said nippers adapted to grip said locking knob at the relative axial displacement of the two cases and secure said cases in their displaced position, inwardly directed protrusions on said nippers, a spring-influenced disengaging element axially shiftable in the rear end of said rear case and adapted to bear against said protrusions to spread said claws to disengage said locking knob, and a compression spring between said two cases adapted to return said cases into their extended position. 5

3. A selective magazine pencil as specified in claim 1, in which the means for locking the cases in their mutually axially displaced positions comprise a locking knob on the rear end of the sleeve, a cup fixed in the rear end of the rear case, a tube fitted in the bottom of said cup, a pair of nippers formed on the front end of said tube and projecting from the bottom of said cup, said nippers comprising claws adapted to grip said locking knob at the relative axial displacement of said cases and to secure said cases in their displaced position, inwardly projecting protrusions on said nippers, a rod axially guided in said tube, a knob on the front end of said rod adapted on the axial displacement of said rod 20 to bear against said protrusions and spread said nippers to disengage said claws from said knob, and a compression spring between said cases adapted to return said cases into their initial position on the disengagement of said claws from 25 said knob. 30

4. A selective magazine pencil as specified in claim 1, in which the means for locking the cases in their mutually axially displaced positions comprise a locking knob on the rear end of the sleeve, a cup fixed in the rear end of the rear case, a tube fitted in the bottom of said cup, a pair of nippers formed on the front end of said tube and projecting from the bottom of said cup, said nippers comprising claws adapted to grip said locking knob at the relative axial displacement of said cases and to secure said cases in their displaced position, inwardly projecting protrusions on said nippers, a disengaging rod 45 axially guided and locked against rotation in said tube, a screw threaded portion on the rear end of said rod, a cap screwed on said screw threaded portion of the rod and adapted to axially displace said rod, a spring in said tube tending to press said cap in outward direction, a knob on 50 the front end of said rod adapted on the axial displacement of said rod to bear against said protrusions and spread said nippers to disengage said claws from said knob, a compression spring between said cases adapted to return said cases 55 into their initial position on the disengagement of said claws from said knob, and a magazine for spare leads formed by the outer wall of said tube the inner wall of said cup, the outer wall of said cup and the inner wall of said rear case, said 60 cup forming a lid for said magazine. 65

WILHELM DÜRRLER.
